UNITED STATES PATENT OFFICE.

JAMES F. LEGATE, OF LEAVENWORTH, KANSAS.

CINDER AND DUST ARRESTER.

SPECIFICATION forming part of Letters Patent No. 244,630, dated July 19, 1881.

Application filed April 30, 1881. (No model.)

To all whom it may concern:

Be it known that I, JAMES F. LEGATE, of Leavenworth, in the county of Leavenworth, and in the State of Kansas, have invented 5 certain new and useful Improvements in Cinder and Dust Arresters; and I do hereby declare that the following is a full, clear, and exact description thereof, reference being had to the accompanying drawings, and to the letters of reference marked thereon, making a part of this specification.

This invention has for its objects to provide a device that may be placed or fitted in a car-window, and which will receive and arrest all 15 sparks, cinders, and dust, and deliver pure air to the interior of the car. These objects I attain by the devices illustrated in the accompanying drawings, in which—

Figure 1 illustrates a perspective view of 20 my improved device, with a portion of the outer wall broken away, showing the interior; Fig. 2, a transverse sectional view of the device; and Fig. 3 a sectional view of the funnel detached.

25 The letter A indicates a box or chamber, constructed of any suitable material and of such size and shape as to fit within the lower part of a car-window. The said box or chamber is divided by means of a foraminous partition, I, into two compartments, B and C.

30 D indicates a door located at the top of the box or chamber, which may be opened or closed at will.

The letter F indicates a funnel, which is constructed with an interior telescopic section, E, which can be moved in and out and held in any desired position by means of set-screws a. The said funnel connects, by means of a pipe,

G, with the interior of the lower compartment, C, of the box A, as indicated in Fig. 1 of the 40 drawings.

The letter H indicates a bent pipe extending from the lower compartment, C, of the box or chamber A outside of the same.

In practice the chamber or box A is fitted 45 or set in the lower part of a car-window, the body of said box or chamber extending outside, with the funnel projecting laterally from such box or chamber. The lower compartment, C, is filled with water up to the level of 50 the inner end of the tube H. The sparks, cinders, and dust, with the external air, enter the car through the funnel E and pipe G, passing under the water in compartment C, which will arrest and hold all impurities, permitting the 55 air to pass upward through the foraminous partition and into the car when the door D is opened. The pipe H serves to permit any superfluous water which may find its way into the chamber C in rain-storms to escape. 60

Having thus described my invention, what I claim, and desire to secure by Letters Patent, is—

The combination of the box or chamber A, the foraminous partition I, the funnel E and 65 its extensible interior section, the pipe G, leading into the compartment C, and the pipe H, all arranged with respect to each other substantially as and for the purposes specified.

In testimony whereof I affix my signature in 70 presence of two witnesses this 30th day of April, 1881.

JAMES F. LEGATE.
